(57) **CLAIM**

The ornamental design for a multi-processor and modular wear protection system, as shown and described.

DESCRIPTION

FIG. 1 is a front top left perspective view of a multiprocessor and modular wear protection system showing my new design, the rear top right perspective view being identical, and the front top right perspective and rear top left perspective views being mirror images thereof, the indicia being no part of the claimed design;

FIG. 2 is a front bottom left perspective view thereof, the rear bottom right perspective view being identical, the front bottom right perspective and rear bottom perspective views being mirror images thereof;

FIG. 3 is a front bottom left perspective view shown in use condition; and,

FIG. 4 is a front left perspective view, the front right perspective view being a mirror image thereof when in the separated configuration.

The broken line showing the mounting areas for the multiprocessor and modular wear protection system in FIGS. 3 and 4, and the extra multi-processor and modular wear protection system in FIG. 3 is included for the purpose of illustrating environmental structure only and forms no part of the claimed design.
